CLAW CONDITIONER FOR ANIMALS

Robert C. Greider, E. 734 38th Ave., Spokane, Wash.

Filed Sept. 13, 1965, Ser. No. 86,966

Term of patent 14 years

(Cl. D12—2)

FIG. 1

FIG. 2

FIG. 3

FIG. 4

FIG. 1 is a perspective view of a claw conditioner for animals taken from the front side thereof, showing my new design.

FIG. 2 is a perspective view taken from the rear and opposite side of that shown in FIG. 1;

FIG. 3 is an end elevational view; and

FIG. 4 is a side view.

I claim:

The ornamental design for a claw conditioner for animals, substantially as shown.
